UNITED STATES PATENT OFFICE

155,967

DESIGN FOR A WASTEPAPER BASKET

Thomas F. Brennan, Valhalla, N. Y., assignor to American Can Company, New York, N. Y., a corporation of New Jersey

Application March 8, 1946, Serial No. 127,216

Term of patent 14 years

(Cl. D58—4)

To all whom it may concern:

Be it known that I, Thomas F. Brennan, a citizen of the United States of America, residing at Valhalla, in the county of Westchester and State of New York, have invented a new, original, and ornamental Design for a Wastepaper Basket, of which the following is a specification, reference being had to the accompanying drawings, forming a part thereof.

Fig. 1 is a perspective view of a wastepaper basket, showing my new design;

Fig. 2 is a side view thereof;

Fig. 3 is an end view; and

Fig. 4 is an enlarged sectional view thereof taken substantially on the line 4—4 of Fig. 2.

I claim:

The ornamental design for a wastepaper basket, as shown.

THOMAS F. BRENNAN.
